UNITED STATES PATENT OFFICE.

COLUMBUS J. EDWARDS, OF STOCKTON, CALIFORNIA, ASSIGNOR OF ONE-HALF TO WILLIAM R. YOUNG, OF STOCKTON, CALIFORNIA.

VARIABLE AUTOMATIC EXHAUST.

SPECIFICATION forming part of Letters Patent No. 782,117, dated February 7, 1905.

Application filed November 10, 1904. Serial No. 232,064.

To all whom it may concern:

Be it known that I, COLUMBUS J. EDWARDS, a citizen of the United States, residing at Stockton, in the county of San Joaquin and State of California, have invented certain new and useful Improvements in Variable Automatic Exhausts; and I do declare the following to be a full, clear, and exact description of the invention, such as will enable others skilled in the art to which it appertains to make and use the same, reference being had to the accompanying drawings, and the characters of reference marked thereon, which form a part of this specification.

15 My invention relates to improvements in exhaust-regulators used in locomotives and other engines; and it consists in the peculiar construction and adaptation of parts herein fully set forth, and particularly pointed out 20 in the claims appended.

My object is to produce such an exhaust-regulator as will automatically regulate the amount of draft in the smoke-stack necessary for the accomplishment of the heavy or light 25 work which the engine may be doing. This object I accomplish by the arrangement within the stack of a ball check-valve secured to the exhaust-pipe and suitably regulated by means of a spring and lever mechanism, which 30 is fully described herein and illustrated in the accompanying drawings.

This specification is an exact description of one example of my invention, while the claims define the actual scope thereof.

35 Reference is to be had to the accompanying drawings, in which similar characters of reference indicate corresponding parts in the several views.

Figure 1 is a sectional view of my improved 40 device as it appears when located within the stack of a locomotive. Fig. 2 is a top view of an exhaust-pipe. Fig. 3 is a side view of a regulating-wedge.

1 designates the boiler of a locomotive, and 45 2 the stack thereof.

3 is the exhaust-pipe, suitably connected to the cylinders by means of the usual pipes 4.

5 is a T-joint secured to the pipe 3 by means of set-screws 6 or by any other suitable means.

In the upper part of said T-joint is screwed a 50 vertical pipe 7, flaring a little at its upper end for the purpose hereinafter specified. Within said pipe 7 are secured two cross guide-bars 8, provided with circular orifices 9 in the center thereof. Said orifices are slightly tapered toward their upper ends for the purpose to be hereinafter shown. Within the other opening of the T-joint is screwed a horizontal pipe 10, which pipe extends out through the side of the stack. Within said pipe 10 is 55 secured a guide-bar 11, provided with a central orifice similar to the orifices 9. On the outer end of said pipe 10 is screwed a cap 12, provided with a central orifice for a purpose to be shown. Said cap is secured in position 60 by means of a set-screw 13.

14 is a vertical plate secured to the outside of the cap 12, said plate having an orifice coinciding with that in the said cap. On the lower end of said plate are two lugs 15, forming component parts of the said plate and spaced apart for the purpose of allowing the insertion of a wedge 16, which wedge is provided with a longitudinal slot 17, adapted to receive the plate 14. On the outer end of 70 said wedge is a suitable pin 18, to which may be connected a lever or the like, which lever leads to the cab or any other suitable place. On the upper end of said plate 14 is fastened a spring 19, regulated by means of a set-screw 20. The top of said spring is pivotally secured to a lever 21, whose fulcrum 22 is pivotally secured to the plate 14 just below the pipe 10. The tension of the spring 19 holds the lower end of said lever 21 firmly in 75 contact with the side of the wedge 16. A rod 23 is pivotally secured to the said lever 21 and extends through the orifices in the cap 12 and the plate 14 and also through the orifice in the guide-bar 11.

24 is an ordinary stuffing-box secured in the orifices in the cap 12 and the plate 14 and surrounding said rod 23. A toggle-joint 25 connects said rod 23 to one arm of a bell-crank 26, which is pivotally mounted on a 95 shaft 27, which shaft is seated in the side walls of the T-joint 5. A similar toggle-joint 25 connects the other arm of said bell-crank to

a rod 28, which rod extends up through the orifices 9 to a point a little lower than the top of the pipe 7. On the upper end of this rod 28 is secured a ball 29, which ball is adapted 5 to fit between the flare of the said pipe 7.

30 is an exhaust-guide removably secured on the top of the pipe 7 and is adapted for use in small stacks, so as to produce a better draft. In large stacks it may be dispensed 10 with entirely.

The operation is as follows: When the engine is running on an easy pull, the wedge 16 is pulled out until the lower end of the lever 21 presses against the said wedge near the tapered end thereof. This draws the ball 29 down until it nearly closes the pipe 7. Thus when the steam from the cylinders passes into the pipe 7 the resistance caused by the said ball will cause said steam to rush past the 15 same with considerable force, thus creating a sufficient draft in the stack. If when the engine was running in the easy manner, as above stated, it should suddenly come to a slight grade or if some other occasion should 20 arise for a greater steam-pressure, then the force of the steam rushing into the pipe 7 automatically lifts the ball 29, and thus allows the said steam to escape without trouble. After the said steam-pressure had again less- 25 ened the spring 19 would force the said ball back into the desired position. If the engine is doing continuous heavy work, the wedge 16 is shoved in until the said lever 21 presses against the said wedge at its widest point, 30 and thus the ball 29 is pressed upward, leaving a sufficient open space for the steam to escape from the pipe 7.

The tension of the spring 19 is regulated by means of the set-screw 20. The guide 30 is only used in small stacks, so as to force the steam straight up and not have it strike the sides of the stack, and thus tend to burn it out. The force of the steam rushing from the cylinders carries all the waste lubricant 45 from the said cylinders into the T-joint 5, and thus automatically lubricates the mechanism within said T-joint. The stuffing-box 24 prevents the steam from escaping out the outer end of the pipe 10.

50 I have entered into a detailed description of the construction and relative arrangement of parts embraced in the present and preferred embodiment of my invention. I do not desire, however, to be understood as confining myself to such specific detail, as such changes and modifications may be made in practice as fairly fall within the scope of my claims.

Having thus described my invention, what 1 claim as new and useful, and desire to protect by Letters Patent, is—

1. In a device of the kind described the combination of a smoke-stack, a vertical exhaust-pipe extending upwardly into said stack, a horizontal pipe leading at right angles from 65 said vertical pipe and out through the side of

said stack, and a spring-actuated ball-valve mechanism arranged without and within said pipes for the purpose of regulating the force of the steam passing from the said vertical pipe, as specified.

2. The combination in an engine of the smoke-stack, a vertical exhaust-pipe leading upwardly into said stack, cross guide-bars arranged within said vertical pipe, central orifices in said bars, a vertical rod extending 70 through said orifices, a ball secured on the upper end of said rod above said vertical pipe, and means attached to the lower end of said vertical rod for regulating the position of said rod and ball, as specified.

3. The combination in an engine of a smoke-stack, a vertical exhaust-pipe leading upwardly into said stack, cross guide-bars arranged within said vertical pipe, central orifices in said bars, a vertical rod extending 75 through said orifices, a ball secured on the upper end of said rod above said vertical pipe, means attached to the lower end of said vertical rod for regulating the position of said rod and ball, and an exhaust-guide removably attached to said vertical pipe near the top thereof, all as set forth.

4. The combination in an engine of the smoke-stack, a vertical exhaust-pipe extending upwardly into said stack, cross guide-bars secured in said vertical pipe, central orifices in said bars, a vertical rod extending through said orifices, a ball secured on the top of said rod outside of said vertical pipe, a horizontal pipe leading outwardly at right angles from said vertical pipe and out through the side of said stack, a cross guide-bar secured within said horizontal pipe, a central orifice in said bar, a centrally-orificed cap on the outer end of said horizontal pipe, a horizontal rod seated in 100 said last-named orifices, means within the said vertical pipe for connecting said first-named rod to said last-named rod, and means connected to the outer end of said last-named rod 105 for regulating the position of the mechanism within said pipes, as specified.

5. The combination in an engine of a smoke-stack, a vertical exhaust-pipe extending upwardly into said stack, cross guide-bars secured in said vertical pipe, central orifices in 110 said guide-bars, a vertical rod extending through said orifices, a ball secured on the top of said vertical rod above said vertical pipe, a horizontal pipe leading at right angles to said vertical pipe and out the side of said stack, a cross guide-bar secured in said horizontal pipe, a central orifice in said guide-bar, a centrally-orificed cap secured over the outer end of said horizontal pipe, a horizontal rod seated in said last-named orifices, a stuffing-box surrounding said horizontal rod where it passes through the orifice in said cap, a bell-crank pivotally mounted in the said vertical pipe, a toggle-joint connecting one arm 115 of said bell-crank to the lower end of said 120

vertical rod, a similar toggle-joint connecting the other arm of said bell-crank to the inner end of said horizontal rod, and means secured to the outer end of said horizontal rod for regulating the position of said horizontal rod, vertical rod, and said ball, as specified.

6. The combination in an engine of a smoke-stack, a vertical exhaust-pipe leading upwardly into said stack, cross guide-bars secured in said vertical pipe, central orifices in said guide-bars, a vertical rod extending through said orifices, a ball secured on the top of said rod and above the said vertical pipe, a horizontal pipe leading at right angles from the said vertical pipe, and out the side of the stack, a cross guide-bar secured in said horizontal pipe, a central orifice in said guide-bar, a centrally-orificed cap secured over the outer end of said horizontal pipe, a horizontal rod seated in said last-named orifices, a stuffing-box surrounding said horizontal rod where it passes through the orifice in the said cap, a bell-crank pivotally mounted in the said vertical pipe, a toggle-joint connecting one arm of said bell-crank to the lower end of said vertical rod, a similar toggle-joint connecting the other arm of said bell-crank to the inner end of said horizontal rod, a vertical plate secured to the outer side of said cap, and a spring-operated lever having its fulcrum pivotally secured to said plate, the said lever being pivotally fastened to the outer end of said horizontal rod, substantially as set forth herein.

35 7. The combination in an engine of a smoke-stack, a vertical exhaust-pipe extending upwardly into said stack, cross guide-bars secured in said vertical pipe, central orifices in said cross-bars, a vertical rod extending through said orifices, a ball secured on the top of said vertical rod outside of said vertical pipe, a horizontal pipe leading at right angles from said vertical pipe and through the side of said stack, a cross guide-bar secured in said horizontal pipe, a central orifice

in said guide-bar, a centrally-orificed cap secured over the outer end of said horizontal pipe, a horizontal rod seated in said guide-bar and cap, a bell-crank pivotally secured in the said vertical pipe, a toggle-joint connecting one arm of said bell-crank to the lower end of said vertical rod, a similar toggle-joint connecting the other arm of said bell-crank to the inner end of said horizontal rod, a stuffing-box surrounding said horizontal rod where it passes through the orifice in the said cap, a vertical plate secured to the outside of said cap, two lugs on the lower end of said plate said lugs being spaced apart, a slotted guide-wedge fitted over said plate and between said lugs, and a spring-regulated lever having its fulcrum pivotally secured to said plate, said lever being pivotally secured to the said horizontal rod and having its lower end always pressing against the side of the wedge, as set forth herein.

8. The combination in an engine of a vertical plate secured to the engine alongside the smoke-stack, two lugs on the lower end of said plate said lugs being spaced apart, a steel spring secured to the said plate at the top thereof said spring being regulated by means of a set-screw, a downwardly-extending lever pivotally secured to the top of said spring, the fulcrum of said lever being pivotally secured to said plate, a slotted wedge fitted over said plate between said lugs, the side of said wedge coming in contact with the lower end of said lever, and means secured to said lever and extending within the said stack for the purpose of regulating the exhaust within said stack all substantially for the purpose fully set forth herein.

In testimony whereof I have signed my name to this specification in the presence of two subscribing witnesses.
